UNITED STATES PATENT OFFICE

104,922

DESIGN FOR A VISE FOR PISTON PINS OR THE LIKE

Rainsford French, Washington, D. C.

Application April 10, 1937, Serial No. 68,674

Term of patent 14 years

To all whom it may concern:

Be it known that I, Rainsford French, a citizen of the United States, residing at Washington, District of Columbia, have invented a new, original, and ornamental Design for a Vise for Piston Pins or the like, of which the following is a specification, reference being had to the accompanying drawing, forming part thereof.

The figure is a perspective view of the vise for piston pins or the like showing my new design.

I claim:

The ornamental design for a vise for piston pins or the like, substantially as shown.

RAINSFORD FRENCH.
